FRANK M. SLOUGH, OF ELYRIA, OHIO, ASSIGNOR TO THE GARFORD MANUFACTURING COMPANY, OF ELYRIA, OHIO, A CORPORATION OF OHIO.

TELEPHONE SYSTEM.

1,169,291.

Specification of Letters Patent. Patented Jan. 25, 1916.

Application filed October 18, 1913. Serial No. 795,922.

To all whom it may concern:

Be it known that I, FRANK M. SLOUGH, a citizen of the United States, residing at Elyria, in the county of Lorain and State of Ohio, have invented certain new and useful Improvements in Telephone Systems; and I do hereby declare the following to be a full, clear, and exact description of the invention, such as will enable others skilled in the art to which it appertains to make and use the same.

My invention relates to telephone systems and more particularly to systems which are adapted to ring the subscriber automatically after the connection has once been set up.

One of the objects of my invention is to provide means for removing the ringing current from the key shelf so as to prevent any possibility of injury by the high voltage ringing current to the switchboard apparatus or the switchboard operators, and to simplify the wiring of the system and providing what is spoken of in the art as a "remote control" for the ringing current.

Another object of my invention is the provision of means for insuring the disconnection of ringing current from line when the subscriber responds, even though the influence caused by the response of the subscriber is very slight.

Another object of my invention is to provide in connection with the apparatus for accomplishing the other objects, means for preventing the application of ringing current to a line upon which a subscriber is already connected in circuit.

Another object of my invention is to accomplish the above-named objects without necessitating the carrying of high voltage alternating ringing current into the manual ringing keys.

In previous attempts to provide systems which will cause automatic disconnection of the ringing current upon the response of the called subscriber, difficulty has been encountered, particularly when the subscriber's station is located on a party line, and when the party line is of the type generally known in the art as a harmonic party line. The difficulty referred to is due to the fact that in such a system as the latter, ringing currents of both low and high frequencies are used and quite often the high frequency ringing current is of higher voltage than the ringing current of low frequency. It has been

found in practice that when many substations are placed on a line near to the telephone exchange, the ringing current sent out from the central exchange, which is ordinarily employed to do a great deal of the work of disconnecting itself automatically upon the response of the called subscriber, is, even prior to such a response, of greater volume than the total volume of current flowing from the exchange upon the response of the subscriber on a line in a party line and of considerable length. I, therefore, provide means to diminish the effect of the alternating ringing current to a degree proportional to its frequency. At the same time the effect of the direct current is diminished but slightly. I do this in such a way that the relay used for the purpose of initially causing the disconnection of the ringing current can also be used for the purpose of controlling the supervisory signals without affecting the talking qualities of the system.

Other objects of my invention and the invention itself will be better understood from a description of the particular embodiment illustrated in the accompanying drawings.

Figure 1 illustrates a telephone system in which my invention is embodied. Fig. 2 illustrates a second telephone system employing a trunk circuit in which my invention is employed.

Referring now to the drawing, and to the particular embodiments of the invention shown therein, at A I have shown the main station, sometimes known as the central station, and at which the switchboard is located. A plurality of substations are shown, one at B upon a telephone line 1-2, which leads from the station B to the station A terminating preferably in a plurality of jacks, one of which is shown at J. Other substations are shown at C, D, E and F, all of which may be upon the same telephone line 3-4, which leads to the main station A, terminating thereat preferably in a jack J'. At the main station I show apparatus for connecting telephone lines together, which may consist of a cord circuit. In the form shown, the cord circuit terminates in plugs P and P', which together with the jacks J and J', illustrate a form of switching means for connecting the apparatus at the main station to the subscribers' lines. The cord circuit illustrated is what is known as a

three-conductor cord circuit. These conductors or strands are illustrated at 6, 7 and 8. The line relay for the line 1-2 is illustrated at 9, the line lamp at 10 and the cut-off relay at 11. The answering supervisory signal is illustrated at 111' and the supervisory relays controlling said signal at 12 and 13.

At H is illustrated the battery employed at the main station. While I have illustrated this battery at different positions upon the diagram, it is understood that these may be the same battery, as I have indicated by employing the same reference character for them all.

At 14 is illustrated a relay controlling the central station set; at 15 a relay controlling the cord circuit; at 16, the calling supervisory lamp; at 17 and 18, the calling supervisory relays; at 20, 21, 22 and 23, means for generating current to operate the signals 24 at the subscribers' stations. In the form shown, I have illustrated four calling generators, though any number may be employed. At 25, 26, 27 and 28 I have illustrated interrupters for breaking the calling current into periods. At 29, 30, 31 and 32 I illustrate means for controlling the connection of the calling current to the subscriber's line, here shown as push button ringing keys. At 33, 34, 35 and 36 I illustrate additional means controlling the application of this current to the called subscriber's line, which are here shown as relays. At O I illustrate the central station operator's set.

The purpose of the apparatus, its use and the apparatus itself will probably be better understood from a description of the operation of the apparatus shown in the embodiment, which is as follows:—Assuming that the subscriber at the substation B upon the line 1-2 desires to converse with one of the subscribers, such for example, as subscriber F upon the line 3-4, the receiver 40 is removed from the receiver hook 41, which rises, closing a switch 41-42, and placing the subscriber's set including the transmitter 43 across the subscriber's line in shunt of the bell 24 and condenser 44. Current then flows from ground at G, through the battery H, the relay 9, the switch 45-46 controlled by the cut-off relay 11, side 2 of line, through the bridge of the talking set, the side 1 of line, through the switch 47-48 of the cut-off relay, through the winding of the relay 9 to ground at G¹. Magnet 9 is energized, closing the switch 48'-49 and completing the circuit through the lamp 10 and the battery H. This lamp is placed in such a position that its actuation is noticed by the operator, who inserts the plug P into the jack J, closing a circuit from ground G², through the relay 11, conductor 50, jack 65 contact 51, plug contact 52, third strand 7,

through the coil 53 of the relay 14, battery H and ground G⁴. The magnet 11 is energized, attracting the armatures 46 and 47 and cutting off the line relay and lamp from line. The winding 53 of the relay 14 is energized, pulling up its armatures 54 and 55 and connecting the operator's set O to the line. A second circuit was closed from G², 11, 50, 51, 52, 7, 56, magnet 13, battery H—ground G⁴, energizing the magnet 13, which attracts its armature 57, closing the switch 57-58 in the circuit of the lamp 111', which would be lighted save for the fact that the calling subscriber at B is upon the line, and that when the plug was inserted, a circuit was completed over both sides of line through the calling subscriber's set and the relay 12 in the cord circuit. Owing to the energization of the relay 12, the armature 59 is pulled up, opening the circuit of the lamp 111' at 59-60. The operator then communicates with the calling subscriber, learning what subscriber is desired, which it is here assumed is the subscriber F upon the party line 3-4, though the subscriber desired may be upon an individual line. The operator first tests the called line to learn whether it is busy or not in the manner well known in the art, by touching the tip of the calling plug 20 to the sleeve 63 of the desired line, or in any other manner, as may be preferred. Assuming that it is idle, she first inserts the plug P' into the jack J', completing the connection between the cord and the called line. As soon as the plug is inserted a circuit is completed from G⁵ through the cut-off relay 61—conductor 62—contact 63—contact 64—conductor 65—winding 66 of the relay 14 to battery H and ground at G⁴. The relay 61 is energized, cutting off the line lamp 67 and line relay 68 of the called line. The winding 66 of the relay 14 is energized, which is wound differentially to the winding 53, so that the relay 14 lets go of the armatures 54 and 55, cutting off the operator's set from the connection and making it impossible for it to be re-connected to the cord circuit during the conversation period. A second circuit is completed when the plug is inserted from G⁵-61-62-63-64-65-69—relay 18—H and ground at G⁶. When the relay 18 is energized through this circuit, it attracts its armatures 70 and 71 closing a switch 70-72 for a purpose to be described and 71-73 in the circuit of the lamp 16; which is as follows: G⁶-H-71-73-74-75-76-16 and G⁷. The lamp 16 is operated over this circuit and remains lighted until the called subscriber responds, when it is interrupted in a way to be described. The apparatus is now in a position for the ringing operation, but before proceeding with that, I wish to state that I have provided arrangements for removing 130

the ringing current from the key shelf, and this will be described in describing the application of the ringing current to the line.

Assuming the signal 24 at station F responds to the character of current produced by the generator 23, the operator presses the button 29, closing the switch 29-84 through the winding of relay 33 as follows: ground at G¹⁰, 29-84-33-85-15-78-76-75-74-73-71-H-G⁶, energizing the magnet 33, which attracts its armatures 87 and 88, closing at switch 87-89 and thereby locking itself up, the locking means here being shown as a locking circuit from ground at G¹¹-87-89-33-85-15-78-76-75-74-73-71-H-G⁶. This locking circuit is under the control both of the switching device P'-J' and of the called subscriber, and will remain operative until either the subscriber responds or the plug is withdrawn, thus making it possible for the operator to interrupt the locking circuit should the called subscriber not respond. Also the relay 15 is energized when the foregoing circuit is completed, attracting its armatures 79 and 80, and interrupting the cord circuit at 79-81 and 80-82, cutting off the answering end of the cord circuit and the calling subscriber from the ringing operation, at the same time closing a switch 80-80' for the ringing circuit to be now described. When the armature 88 is attracted a switch 88-90 is closed and a circuit completed as follows: G¹²-23-91-28-92-90-88-93-94-80'-80-6-tip 971—tip spring 98—side 4 of line—the signal 24 at station F—side 3 of line 99-100-8-101-102—battery H to ground at G¹². The commutator 28 is continuously rotated and the circuit of the signaling current is interrupted and made, allowing the ringing current to pass over the line and operate the signal 24 for definite periods of time and interrupting the signaling for definite periods of time. During the silent intervals, battery current is maintained connected to the line by the commutator 28. The current passing through the winding 102 of the relay 17 is not sufficient to operate such relay, owing to the resistance of the bell 24. A part of this current passes through the branch 103-105-104-106-72-70 of this circuit, which includes a non-inductive resistance device 105, and the higher the frequency of current employed, the greater will be the proportion of current passing through the branch 105, since the branch 108 includes an inductive resistance. This ringing continues until the subscriber at F responds by removing the receiver 110 from the switch 111, completing a bridge 112 across the line 3-4, whereupon sufficient current flows to energize the winding 102 of the relay 17, which attracts the armatures 106 and 75. As soon as the armature 106 is attracted, all of the current will flow through the winding 102, thus insuring a positive operation of that relay. The attraction of the armature 75 opens the switch 75-76, removing the locking means from the relay 33, which lets go the armatures 87 and 88 cutting off the ringing generator and also interrupting the locking means. The circuit of the relay 15 is also broken when the switch 75-76 is opened, releasing the armatures 79 and 80 and closing the cord circuit. At the same time, the switch 80-83 will be closed, closing a circuit as follows: G¹³-H-102-108-101-8 through the called line and the called subscriber's set, back to the tip strand 6-80-83-1111 to G¹⁴, over which the relay 17 is held up. The attraction of the armature 75 likewise interrupts the circuit of the lamp 16 at 75-76. The apparatus is now in a position for conversation with the operator locked out and the conversation continues to a termination. Upon either party hanging up, the corresponding supervisory signal is operated, indicating to the operator that the conversation is terminated; for example, assuming that the subscriber at B hangs up, the circuit of the relay 12 will be broken and the circuit of the lamp 111 completed at 59-60. If it is the called subscriber F who hangs up, the circuit of the relay 17 will be interrupted, releasing the armature 75 and closing the circuit of the lamp 16 through 75-76. Observing that the subscribers have completed the conversation, the operator withdraws the plugs P and P', interrupting the circuits of the relays 13 and 18, respectively, and restoring the system to normal. Supposing that the called subscriber did not respond, the operator withdraws the plug P', interrupting the circuit of the relay 18, which in releasing its armature 71, interrupted the locking circuit of the relay 33 at 71-73, restoring the system to normal.

While I have illustrated the connecting apparatus as a cord circuit, the switching means for connecting it to a line circuit as a plug and jack, the locking means for the relay 33 as a locking circuit, the means controlling the connection of the generating means to the cord circuit as including a relay, it will be understood that other suitable forms of this apparatus may be employed. I likewise may employ any suitable form of ringing key or arrangement for initially closing the circuit of the relay 33.

In Fig. 1 I have illustrated my invention employed in connection with a cord circuit, though it may readily be employed with other forms of circuits. In Fig. 2 I have illustrated it as applied to one character of trunk circuit, as there are numerous and divers forms of cord circuits, trunk circuits,

etc., to which my invention may be applied, and I have illustrated it as applied to these only for the sake of explaining my invention, and not that I desire to be limited to 5 these particular forms.

The apparatus shown in Fig. 2 and the object thereof will undoubtedly be well understood from a description of the operation, which is as follows:—At X is shown a telephone line which extends from a subscriber's station at Y to a central station at W, here known as the main central station or A operator's position. At W is arranged a cord circuit adapted to connect a calling line to the 10 trunk circuit. At Z is shown the trunk station or what is known as the B operator's position. At V I show a subscriber's set upon a line U, here known as the called line. In the 15 operation of the system, the A operator at the station W is, in one way or another, informed of the trunk which she is intended to use, which is here assumed to be the trunk illustrated in Fig. 2. The plug P² is inserted into the jack J² of the trunk, 20 completing a circuit as follows: 150—winding 151 of relay 152—153—154—155—156—157—through the high resistance relay 158—159—160—161—162—winding 163 of relay 152—battery 164. The relay 158 will be energized, but the resistance of this relay will 25 be such that the current will not be sufficient to energize the relay 152. The lamp 165 will thus remain lighted. When energized, the relay 158 will draw up its armature 166, closing the switch 167 and the circuit of the 30 signal 168 as follows: 169—168—166—167—171—172—173—ground at 174. The operation of this signal indicates to the B operator that the connection has been made, 35 whereupon she inserts the plug P³ into the jack J³, completing a circuit through the called line cut-off relay 175 and the relay 176 as follows: 177—175—178—179—180—176—173—174. The relay 175 draws up its 40 armatures, cutting off the calling line apparatus Q from the line. The relay 176 attracts its armatures 172 and 181, opening the switch 171—172 and retiring the signal 168. The switch 172—182 is closed for a purpose 45 to be described. The switch 181—183 is closed for a purpose to be described. The operator now actuates one of the set of ringing keys K, selecting the one adapted to place upon the line ringing current of such 50 a character as will operate the signal of the called subscriber. In this instance, we will assume that it is the key K' which is operated, this key controlling the current from the generator 184 which it is assumed produces current suitable for the operation of 55 the bell at the station V. When the key K' is depressed, a contact 186 engages a contact 187, closing a circuit as follows: 188—186—187—189—190—191—245—244—192—194—60 182—172—173 and 174. The relay 189

draws up its armatures 195 and 196, closing a locking circuit for said relay through 195—197 to ground 198. The switch 196—199 is closed, connecting the ringing current to line as follows: 200—181—185—201—199—196—202—203—205—206—207—208—209—210—211—212 to the junction 215 and from thence through the following branches in parallel: 213—214—216—217—218 to 219; the other branch 215—non-inductive 75 resistance 220—221—222—223—183—181—224—225. The interrupter 185 is continuously operating, placing signaling current upon the line at predetermined intervals and maintaining battery connections to the line 80 at alternate intervals. When the called subscriber responds, a low resistance shunt is placed upon the subscriber's line around the signaling set, whereupon the strength of the line current is sufficiently great to 85 operate the magnet 230, attracting its armatures 193 and 222. The armature 193 upon being attracted, closes the circuit of the relay 241 as follows: 174—173—172—182—194—193—243—252—the winding 251 of the 90 relay 241—253, thus energizing the relay 241, which attracts its armatures 244 and 254 for a purpose to be described. During the ringing period the ringing lamp 240 was lighted through the contacts 172 and 182 of 95 the relay 176. However, when the relay 241 was energized a circuit of the lamp 240 was broken at 244—245, thus indicating to the operator that the called for subscriber has responded. When the armature 244 is 100 attracted it makes a connection with the contact 255, thus closing a locking circuit 192—244—255—251—253—174—173—172—182 and 194 for the relay 241, thus causing it to remain energized until the connection 105 is taken down, when the contacts 172 and 182 will be broken. At the time the relay 230 was energized upon the response of the called for subscriber, the armature 222 was attracted, thus breaking a circuit of the shunt 110 220 about the winding 217, so that the full strength of the battery and ringing current passes through the relay. This insures that the relay 241 shall be positively operated. At the time the ringing lamp is extinguished, the locking circuit of the relay 189 is broken at 244 and 245, thus disconnecting the ringing generator from the line. When the armature 254 of the relay 241 is attracted, a circuit is completed through the 115 relay 234 as follows: 253—254—233—256—the winding of the relay 234 to battery 257, thus energizing the relay 234, which attracts its armatures 235 and 236, closing the trunk 120 conversational circuit. The system is now 125 in condition for conversation, which may now take place. At the end of the conversation, the receivers of the subscribers are returned to the hooks, interrupting the subscribers' bridges. This act at the called sub- 130

scriber's station breaks the circuit of the relay 230, releasing the armatures 193 and 222 and the shunt about the relay 158, which existed while the conversation was in progress. This shunt was of such low resistance as to permit the operation of the relay 152 and extinguishing of the lamp 165. Upon the interruption of this shunt when the called subscriber hangs up his receiver, the 10 resistance of the relay 158 is again placed in circuit with the relay 152, whereupon the circuit of the lamp 165 is again closed, indicating to the A operator that the called subscriber has hung up his receiver, whereupon 15 the plug F² is withdrawn from the jack J², deenergizing the relay 158, completing a circuit through the lamp 168 as follows: 169—168—166—250—251—192—194—182—172—173—174. As soon as this lamp is operated, 20 the B operator withdraws the plug P³ from the jack J³, restoring the system to normal.

I have illustrated my invention in connection with these two forms of circuits simply for the purpose of illustrating the same. I 25 do not wish to be limited to the details of these circuits, but contemplate numerous and extensive departures from such details, being limited only by the scope of the claims.

I claim:—

30 1. In a telephone system, the combination of a main station, a telephone line leading to the main station, a plurality of substations on said line, telephone line connecting apparatus at the main station, switching means for connecting said apparatus to said telephone line, a calling signal device at each substation, a plurality of current producing means at the main station, each adapted to supply current to operate one of said calling 35 signal devices, conductors for connecting said current generating means to said switching apparatus, a plurality of manually operable switches, one for each of said current generating means, conductors for said switches, said last named conductors being independent of the conductors for connecting the current generating means to the switching apparatus, mechanism controlled by said switches and means including a local 40 circuit at the main station controlling the application of current generated by said current generating means to the telephone line controlled by said manually operable switches and said mechanism.

45 55 2. In a telephone system, the combination of a called telephone line, a plurality of substations on said line, a ringer at each substation, a main station to which said called line leads, a cord circuit at the main station, a plug for the cord and a jack for the line by which the cord and line are connected together, a plurality of current generators at the main station, each adapted to supply current to operate one of the ringers at one of 60 the substations, a plurality of conductors for

70 connecting said generators to the plug of the cord, a plurality of manually controlled switches, one for each current generator, conductors for said switches independent of the conductors connecting the current generating means to the plug, a plurality of relays, one for each switch, each relay being controlled by a corresponding one of said switches and means including a local circuit 75 controlling the application of current generated by said generators to the telephone line controlled by said manually operated switches and said relays.

3. In a telephone system, the combination 80 of a main station, a called telephone line leading to the main station, a plurality of substations on the line, a ringer at each substation, a cord circuit at the main station, a plug for the cord and a jack for the line through which the line and cord are connected, a plurality of current generators at the main station, conductors for connecting each generator to the plug, a plurality of relays, one controlling the connection of each of said generators to the plug, a circuit local 85 to the main station, including a plurality of branches, one of said relays being in each of said branches, a plurality of manual switches, one in each branch removed from the conductors connecting the generators to 90 the plug and means for locking up each of said relays when its corresponding switch is operated.

4. In a telephone system, the combination 95 of a main station and a plurality of substations, telephone lines connecting said substations to said main station, apparatus at the main station for connecting two of said telephone lines together, switching means for connecting said apparatus to a called 100 telephone line, calling signal devices at the substations, current generators at the main station for supplying current to operate said calling devices, a plurality of ringing switches and a plurality of relays each controlled by a companion ringing switch, a circuit including a plurality of branches, each branch including a relay and a companion ringing switch, means including a portion of 105 said circuit for locking up each relay when its companion ringing switch has been operated, and conductors for connecting the generators to the switching means, said conductors being independent of said circuit branches including said relays and ringing 110 switches.

5. In a telephone system, the combination 115 of a main station, a cord circuit at the main station, a called line leading to the main station, a plurality of substations on said line, a ringer at each substation, a plug for the cord and a jack for the line, by which they are connected together, a plurality of current generating means at the main station, associated with the cord circuit thereat 120

and adapted to supply current to operate the ringers, a ringing circuit including a plurality of ringing leads, one of said generating means being in each of said leads, a 5 ringing relay controlling the ringing circuit, a plurality of branches of said circuit, a relay in each of said branches controlling one of said ringing leads, and a manual switch in each of said branches controlling said 10 ringing relay circuit through its branch and the relay therein, and means for locking the circuit of the ringing relay after any of said switches have been operated.

6. In a telephone system, the combination 15 of a main station, a cord circuit at the main station, a called telephone line leading to the main station, a plurality of substations on the line, a ringer at each substation, switching apparatus for connecting the 20 cord and line together, a plurality of current generating means associated with the cord at the main station and adapted to supply current to operate the ringers at the substations, a ringing circuit, a lead from 25 each of said generating means in said circuit, a ringing relay controlling the ringing circuit, a ringing relay circuit, a plurality of branches of said ringing relay circuit, an electromagnetic relay in each of said 30 branches, each of said last named relays controlling one of said ringing leads, a manually operated switch in each of said branches controlling said ringing relay circuit and an arm of each branch containing normally 35 open contacts controlled by the relay in said branch through which said relay locks the ringing relay circuit when said relay is operated.

7. In a telephone system, the combination 40 of a main station and a called telephone line, link conductors at the main station for connecting telephone lines together, substations on said line, a calling signal at each substation, a plurality of current generating means 45 adapted to produce current to operate the calling signals, a ringing circuit, a ringing lead connecting each of said current generating means in said ringing circuit, a ringing relay, a circuit for the ringing relay, a plurality 50 of branches of said ringing relay circuit, a relay in each of said branches, each of said relays controlling one of said ringing leads and manually controlled contacts in each of said branches controlling said ringing 55 relay circuit.

8. In a telephone system, the combination 60 of a main station and a called telephone line, link conductors at the main station for connecting telephone lines together, substations on said line, a calling signal at each substation, a plurality of current generating means 65 adapted to produce current to operate the calling signals, a ringing circuit, a ringing lead connecting each of said current generating means in said ringing circuit, a ringing 70

relay, a circuit for the ringing relay, a plurality of branches of said ringing relay circuit, a relay in each of said branches, each of said relays controlling one of said ringing leads, manually controlled contacts in each of said branches controlling said ringing relay circuit and means to maintain said circuit closed after said manually controlled contacts have been operated and released.

9. In a telephone system, the combination 75 of a main station and a called telephone line, link conductors at the main station for connecting telephone lines together, substations on said line, a calling signal at each substation, a plurality of current generating means 80 adapted to produce current to operate the calling signals, a ringing circuit, a ringing lead connecting each of said current generating means in said ringing circuit, a ringing relay, a circuit for the ringing relay, a plurality 85 of branches of said ringing relay circuit, a relay in each of said branches, each of said relays controlling one of said ringing leads, manually controlled contacts in each of said branches controlling said ringing relay circuit, and means controlled by 90 said branch relays for maintaining said ringing relay circuit after said manually controlled contacts have been operated and released.

10. In a telephone system, the combination 95 of a main station, telephone line interconnecting mechanism at the main station, a telephone line leading to the main station, switching apparatus for connecting said 100 mechanism to said telephone line, a plurality of signaling devices on the telephone line, a plurality of current generating means, a ringing circuit, ringing leads including said means in said ringing circuit, 105 each lead containing normally open contacts, a ringing relay, a ringing relay circuit including said ringing relay, a plurality of branches of said ringing relay circuit, a magnet in each branch, each magnet controlling the normally open contacts in one of said ringing leads, normally open manually controlled contacts in each of said branches and means for automatically maintaining a 110 branch and said ringing relay circuit after the manually controlled contacts in said branch have been closed and opened.

11. In a telephone system, the combination 115 of a selective signaling circuit, a plurality of electro-responsive devices in said circuit, a plurality of sources of current adapted to be connected in said circuit to supply current to operate said devices, a ringing relay controlling the connection of a source to said devices, a plurality of selective relays, each adapted to include a particular one of said sources of ringing current with the contacts of said ringing relay, a circuit for the magnet of said ringing 120 relay, a plurality of manually operated 125 contacts in each of said selective relays, and means for connecting the contacts of each selective relay to the contacts of the magnet of said ringing relay.

switches, each of said switches being adapted to include a particular selective relay in the circuit of the magnet of said ringing relay, and automatic means to maintain the ringing relay magnet circuit after the restoration of said switch to normal.

12. In a telephone system, the combination of a telephone line, a plurality of substations on said line, each including an electro-responsive device and a manually operable switch, a plurality of sources of current adapted to be connected to said telephone lines to supply current to selectively operate said electro-responsive devices, a ringing relay controlling the connection of said sources of current to said telephone line, a plurality of selective relays, each adapted to include a particular one of said sources of ringing current with the contacts of said ringing relay, a circuit for the magnet of said ringing relay, a plurality of manually operable switches, each of said switches being adapted to include a particular selective relay in the circuit of the magnet of said ringing relay, automatic means to maintain said ringing relay magnet circuit after the restoration of said last named manually operable switch to normal and means controlled by the manually operable switches at the substations for restoring the ringing relay and the selective relays to normal.

13. In a telephone system, the combination of a telephone line, a plurality of substations on said line, each line including a ringer and a hook-switch, a plurality of sources of current, each adapted to be connected to said telephone line to supply current to selectively operate said ringers, a ringing relay controlling the connection of a source of current to said line, a plurality of selective relays, each controlling the connection of a particular one of said sources of ringing current with the contacts of said ringing relay and to said telephone line, a circuit for the magnet of said ringing relay, a plurality of manually operated switches, each of which controls the connection of a particular selective relay in the circuit of the magnet of said ringing relay, automatic means to maintain said ringing relay magnet circuit after the restoration of said switch to normal and means controlled by the hook-switches at the substations for restoring the ringing relay to normal.

14. In a telephone system, the combination of a telephone line, a plurality of substations on said line, each line including a ringer and a hook-switch, a plurality of sources of current, each adapted to be connected to said telephone line to supply current to selectively operate said ringers, a ringing relay controlling the connection of a source of current to said line, a plurality of selective relays, each controlling the con-

nnection of a particular one of said sources of ringing current with the contacts of said ringing relay and to said telephone line, a circuit for the magnet of said ringing relay, a plurality of manually operated switches, each of which controls the connection of a particular selective relay in the circuit of the magnet of said ringing relay, automatic means to maintain said ringing relay magnet circuit after the restoration of said switch to normal and means controlled by the hook-switches at the substations for restoring the selective relays to normal.

15. In a telephone system, the combination of a telephone line, a plurality of substations on said line, connecting apparatus for connecting said telephone line with other telephone lines, signaling means at each subscriber's station, means for generating current to operate said signaling means, a subscriber's telephone at each station, a source of current at the main station for energizing said telephone for talking purposes, a relay at the main station in the circuit of said talking current source, a circuit for connecting said generating means to said subscriber's signaling means, said last named circuit including said relay and a shunt about said relay and contacts on said relay, said contacts being adapted to remove said shunt when the relay is connected in the talking circuit of said subscriber's telephone.

16. In a telephone system, the combination of a main station and a plurality of substations, telephone lines for connecting said substations to said main station, apparatus at the main station for connecting telephone lines together, signaling means at the subscriber's station, means for generating current to operate said signaling means, a relay at the main station controlled by the called subscriber, a circuit for connecting said generating means to the signaling means at the subscriber's station, said circuit including said relay and a shunt about said relay controlled by said relay.

17. In a telephone system, the combination of a plurality of telephone lines, substations on said lines, apparatus for connecting telephone lines together, signaling means at the subscriber's station, means for generating current to operate said signaling means, a subscriber controlled device associated with the connecting apparatus, a circuit for connecting said generating means to said subscriber's signaling means, including said subscriber controlled device and a shunt about said subscriber controlled device controlled by said subscriber controlled device.

18. In a telephone system, the combination of a main station and a plurality of substations, telephone lines for connecting said substations to said main station, ap-

paratus at the main station for connecting telephone lines together, signaling means at the subscriber's station, means for generating current to operate said signaling means, 5 a subscriber controlled device at the main station, a circuit for connecting said generating means to said subscriber's signaling means including said subscriber controlled device and a shunt about said subscriber

controlled device controlled by said subscriber controlled device.

In witness whereof I have affixed my signature in the presence of two witnesses this 15th day of October 1913.

FRANK M. SLOUGH.
